UNITED STATES PATENT OFFICE

128,785

DESIGN FOR A CONTAINER FOR BOTTLED PRODUCTS

Raymond Loewy, New York, N. Y., assignor to
D'Arcy Advertising Co., St. Louis, Mo., a corpora-
tion of Missouri

Application October 30, 1940, Serial No. 96,196

Term of patent 7 years

To whom it may concern:

Be it known that I, Raymond Loewy, a citizen of the United States, residing in the county of New York, city of New York, and State of New York, have invented a new, original, and ornamental Design for a Container for Bottled Products, of which the following is a specification, reference being had to the accompanying drawing, forming a part thereof.

In the drawing: Fig. 1 is a view in perspective of a container for bottled products, showing my new design; Fig. 2 is a top plan view of the container of Fig. 1; Fig. 3 is a side elevational

view of the container as viewed from either side, and Fig. 4 is an end elevational view of the container, as viewed from either end.

The dominant feature of my design resides in a container, the body of which is of generally rectangular outline, characterized by semi-transparent wall and bottom portions, so as to simulate a cake of ice.

I claim:

The ornamental design for a container for bottled products, substantially as shown and described.

RAYMOND LOEWY.
